(57) **CLAIM**

The ornamental design for a two-prong fastening pin, as shown and described.

DESCRIPTION

FIG. 1 is a perspective view of the present invention.

FIG. 2 is a top view of the present invention.

FIG. 3 is a bottom view of the present invention.

FIG. 4 is a right side view of the present invention.

FIG. 5 is a left side view of the present invention.

FIG. 6 is a front view of the present invention; and,

FIG. 7 is a back view of the present invention.
